SAFETY RAZOR WITH ROTARY MAGAZINE
AND BLADE THEREFOR

Joseph C. Fennelly, San Francisco, Calif.

Application March 29, 1947, Serial No. 738,039

18 Claims. (Cl. 30—40)

1

This invention relates to safety razors.

One of the objects of this invention is the provision of curved safety razor blades that are adapted to be compactly and safely arranged in an annular row with their concave sides facing the axis of said row and generally concentric therewith, the said blades being of the thin, wafer-type so as to enable flexing them from their curved form to a more or less flattened shape against the inherent resiliency of the blades tending to urge them back to their curved form.

Another object of the invention is the provision of a magazine of curved safety razor blades arranged in an annular row with their cutting edges being straight and extending generally axially of said row but directed substantially circumferentially of said row, and which blades are of the relatively thin, resilient, flexible wafer-type so that the cutting edges may be swung outwardly of the row against the inherent resiliency of the blades to positions directed generally tangentially of the row.

A still further object of the invention is the provision of a magazine of curved safety razor blades arranged in an annular row with their cutting edges straight and extending generally axially of the row but directed substantially circumferentially of the row, and which blades are of the relatively thin, resilient flexible wafer-type, and which magazine is provided with means for urging each blade outwardly along its cutting edge at a point around said row and against the tension of each blade so as to move the cutting edge to shaving position.

An additional object is the provision of a safety razor having a tubular head adapted to receive therein a magazine of curved relatively thin, flexible wafer-type blades arranged in a row and provided with means for flexing each blade of said magazine outwardly of the row along the cutting edge of each blade so as to enable such edge to move outwardly of a side of said head to shaving position.

Heretofore attempts to arrange razor blades about an axis for individual movement to a shaving position has either required a relatively complicated mechanism for moving the blades radially inwardly and outwardly of such axis or else the entire assembly of blades must be moved, thus requiring a large and unsightly head or hinged sides on the head or both, and in most instances the cutting edges of the blades are exposed and project a substantial distance outwardly whereby the fingers of the operator are in constant danger of being cut while attempting to change magazines and the edges are unprotected from injury.

In most safety razors of the rotary magazine type it is very difficult to position the blade that is to be used at the proper and desired angle

2

relative to the handle and to keep the razor compact and simple and to provide a compact and simple magazine of blades.

One of the objects of this invention is the provision of blades, magazine and razor that overcomes all of the above objections.

Other objects and advantages will appear in the description and in the drawings.

In the drawings,

10 Fig. 1 is a perspective view of a safety razor embodying the present invention.

Fig. 2 is a perspective view of a magazine of blades for the razor of Fig. 1, said magazine being separate from the razor.

15 Fig. 3 is an enlarged longitudinal sectional view taken through the head of the razor.

Fig. 4 is a sectional view taken along line 4—4 of Fig. 3.

20 Fig. 5 is an enlarged perspective view of one of the safety razor blades separate from the magazine.

Fig. 6 is an enlarged part sectional, part elevational view of the support for the blades for forming the magazine.

25 In detail, the safety razor illustrated in the drawings comprises a handle 1, head 2 and magazine 3.

30 The head, generally designated 2, is tubular and preferably cylindrical with a cylindrical wall 3, one side of which is formed with a slot 4 extending longitudinally thereof through which each blade is adapted to extend as used. Conventional comb teeth 5 are along one side of the said slot and the usual end lugs 6 project from the side of the wall 3 adjacent the opposite ends of the slot for supporting the ends of the blade that is adapted to project through the slot, as will later be described more in detail.

35 The handle 1 is secured at one end to one side of the head 2 and projects from said head.

40 The tubular head 2 is provided with an end wall 7 that is rigid therewith and that closes one end of said head. This end wall has a hollow central cylindrical core member 8 that extends from end wall 7 through the head coaxial with the latter and spaced within the cylindrical wall 3, leaving an annular space between the wall 3 and member 8 in which the blade magazine is adapted to be received, as will later be described more in detail. The end of head 2 opposite end wall 7 is open except when a magazine of blades is in the head, and the same is true of the end of member 8 that is opposite end wall 7.

45 The magazine itself comprises a tubular body 10 (Fig. 6) that is preferably cylindrical and of a diameter to slip over the core member 8 (Fig. 3). This body 10 is formed with two spaced rows of openings 11, the said rows extending circumferentially of the body and being adjacent but spaced from opposite ends of said body. The

openings in each row are the same in number and are correspondingly positioned around the body. Also the openings are of the same size and each is elongated circumferentially of the body.

The core member 8 is formed with a pair of openings 12 that are respectively adapted to register with an opening in each of the rows of openings 11 upon rotation of the body 10. However, openings 12 are not elongated, but are circular.

Within the core member 8 is a spring 13 that is bent on itself so that opposite end portions 14 of said spring will extend alongside each other and alongside the central portion 15 of the spring with the terminating ends 16 bent at about right angles to portions 14 for extending through the openings 11, 12. The said end portions 16 are tapered as at 17 at their outermost ends to facilitate rotation of the body 10, as will be described. The bend at the juncture between end portions 14, 16 provides a stop for limiting the extent that said end portions 16 will project through the openings 12.

The outer side of body 10 is formed with a plurality of circumferentially progressively deepened recesses 20 that extend longitudinally of the body 10 substantially from one end to the other. A square shoulder 21 is at the deepest end of each recess while the opposite end is even with the outer surface of the body in direction circumferentially of the latter. The openings 11 extend through the bottom of each such recess, the latter being at equal distances around the body.

In Fig. 4, for example, there may be eight of the recesses 20. This number may vary. In each recess is seated a safety razor blade 22 that is generally rectangular and elongated and each blade is curved transversely of its length with the straight back edge against shoulder 21 on body 10. The straight longitudinally extending edge 23 (Figs. 4, 5) is sharpened and oppositely outwardly extending projections 24, 25 are at the opposite ends of the back edge. The projection 24 is shorter than projection 25 but both may be of the same length, if desired.

The concave sides of the blades 22 face toward the central axis of the body 10 and the curvature of each blade is preferably about a slightly shorter radius than the periphery of the body 10.

The distances between adjacent shoulders 21 is substantially less than the widths of the blades 22, therefore, the marginal portion of each blade along its cutting edge will overlap the marginal portion of the adjacent blade that is along the rear edge of the latter. In this manner the blades will tightly hug the body and each other so that the edges will not be exposed to damage nor will they cut the fingers of an operator handling them.

The blades 22 are snugly held against the body 10 and in said overlapping relation by end flanges 26 that are crimped over the projections 24, 25 at the ends of the blades. The flange extending over projection 25 is preferably knurled as indicated in Fig. 1 to facilitate grasping by the fingers for rotating the magazine inasmuch as this flange will project from the open end of the head 2 when the magazine is in the head. The end of the body 10 that projects from the body is closed by a plate 27 that may be secured to the body in any suitable manner.

While, as already stated, the projections 24, 25 may be of the same size, the projection 25 is

preferably slightly longer thus leaving a slight gap between the flange 26 that extends over the same and the adjacent end of the head 2, thereby enabling the operator to more readily withdraw the magazine from the head. This gap is very small, but it is sufficient to receive the thumb nail or the like, if the magazine should tend to stick after a relatively long non-use of the razor.

Referring to Fig. 5, it will be noted that each of the blades 22 is formed with a pair of slots 30 that open outwardly of the rear edge of each blade. These slots are spaced so as to register with openings 12 in core member 8 when the magazine of blades is within the head. In Fig. 4 it will be seen that the slots 30 of one blade of each adjacent pair thereof is overlapped by the imperforate portion of the other blade. Thus the end 16 of spring 13 will project through the slots in the underlying blade and will engage the inner side of the overlying blade forcing the latter outwardly.

The ends 16 of spring 13 are adjacent the inner end of slot 4 in head 2, as best seen in Fig. 4, and are slightly spaced from said inner end. The blades on the magazine are arranged so that a counterclockwise turning of the magazine by a finger gripping the knurled outer flange 26 of said magazine will move the blades with their cutting edges leading.

In operation the magazine with the blades all snugly fitting around the body, as seen in Fig. 2, is slipped into the open end of head 2 and is moved into said head as far as it will go. As soon as the magazine is in the head the latter is rotated clockwise, as seen in Fig. 4, until the ends 16 of the spring 13 snap through openings 11 in the body 10, and as soon as this occurs the ends 16 will also extend through the slots 30 in the underlying blade of a pair of the latter, thus forcing the outer or overlying blade outwardly away from the body 10. The blade 31 in Fig. 4 is in the position of the blade that is so forced outwardly. Upon rotating the magazine counterclockwise, as seen in Fig. 4, the outwardly urged blade will move through the slot 4 in head 2 to the shaving position as indicated by blade 32 in Fig. 4. The stops on the ends of lugs 6 will limit the movement of blade 32 through slot 4. The razor is now ready for use in shaving.

After the operator has shaved, the razor is readily cleaned with water and if desired, the blade 32 may be moved back into the head 2 by rotating the magazine clockwise until ends 16 of spring 13 are in the next pair of openings in body 10. Blade 32 will be then in the position occupied by blade 31 and to obtain a fresh blade the operator will merely rotate the magazine clockwise until ends 16 project through the next pair of openings in body 10 and a counterclockwise movement will bring the fresh blade into operating position.

If desired, the magazine may be withdrawn for cleaning, since water may readily be flushed into the magazine from its open end and also the inside of the head is readily cleaned. The blades and body of the magazine, as well as the head 2, are preferably of rustless and non-corrosive material.

The provision of pre-curved blades enables the assembly of a compact magazine, the outer side of which is defined by the blades themselves, and their cutting edges are directed circumferentially of the annular row of blades in the magazine.

When it is considered that the blades are relatively thin and of the wafer type, it will be seen that the cutting edges of the blades while exposed are not readily susceptible to injury nor to being injured. Also the method of flattening the blades for shaving against the tension of the latter enables an accurate control of the cutting edge.

It has further been found that by pre-curving the blades the final honing and stropping are facilitated since the blades may be revolvably supported for these operations with the blades revolving in one direction only.

It is to be understood that the detailed description and drawings are not to be considered restrictive of the invention but merely illustrative of a preferred form.

I claim:

1. A flexible resilient wafer-type single edged, safety razor blade having a straight cutting edge and being precurved to said edge with a substantially uniform radius of curvature in its dimension at right angles to said edge for self retention of said curve, projections adjacent the edge of said blade opposite said cutting edge and extending oppositely outwardly beyond the ends of said cutting edge to permit securement of said blade in a rotary magazine by means of said projections.

2. In a safety razor, a flexible resilient wafer-type safety razor blade having a straight cutting edge and being pre-curved to said edge in its dimension at right angles thereto for self retention of said curve, means spaced from said cutting edge for securing said blade on a supporting magazine in its curved form and a blade magazine to which said blade is so secured with said edge closely adjacent said magazine and with the portion of said blade between said means and said edge free for movement outwardly relative to the concave side of the blade.

3. A blade supply magazine for a safety razor comprising an annular row of thin, resilient flexible blades having straight cutting edges extending axially thereof, said blades being pre-curved to substantially correspond with the curvature of said row in a direction transversely of their said edges, and means supporting said blades in said row with their concave sides facing the axis of said row.

4. A blade supply magazine for a safety razor comprising an annular row of thin resilient flexible blades having straight cutting edges extending axially thereof, said blades being pre-curved to substantially correspond with the curvature of said row in a direction transversely of their said edges and being positioned with their said edges facing substantially circumferentially of said row, and means supporting said blades in said row with their concave sides being substantially uniformly spaced from the central axis of said row.

5. A blade supply magazine for a safety razor comprising an annular row of thin resilient flexible blades having straight cutting edges extending generally axially thereof, said blades being uniformly curved from a point adjacent said edges circumferentially of said row, means spaced from the cutting edge of each blade for securing said blades in said row with the portion of each blade between said means and said cutting edge being yieldably urged generally radially inwardly of said row, but free for movement of the cutting edge generally radially outwardly against the tension of said portion.

6. A blade supply magazine for a safety razor

comprising an annular row of thin resilient flexible blades having straight cutting edges extending generally axially thereof, said blades being uniformly pre-curved circumferentially of said row, with the marginal portion of each blade along its cutting edge overlapping the blade adjacent said cutting edge in close relationship thereto, means supporting said blades in said row with their concave sides facing the central axis of said row.

7. A blade supply magazine for a safety razor comprising an annular row of elongated thin resilient flexible blades having straight cutting edges extending generally axially thereof and longitudinally of said blades, said blades being uniformly curved circumferentially of said row, projections on the ends of said blades spaced from their cutting edges, a rigid holder in engagement with said projections for securing said blades in said row.

8. A blade supply magazine for a safety razor comprising an annular row of thin resilient flexible blades having straight cutting edges extending generally axially thereof, said blades being uniformly curved circumferentially of said row, a cylinder within said row coaxial with the latter, means carried by said cylinder spaced from the said cutting edges securing said blades to said cylinder with the concave sides of said blades substantially against said cylinder.

9. A blade supply magazine for a safety razor comprising an annular row of thin resilient flexible blades each having a straight cutting edge extending generally axially of said row, said blades being curved circumferentially of said row, means spaced from the cutting edge of each blade for securing said blades in said row with the portion of each blade along its cutting edge being free for movement generally radially outwardly thereof against the tension of the blade whereby the cutting edge of each blade may be moved from a position directed substantially circumferentially of said row to a position directed tangentially thereof.

10. A blade supply magazine for a safety razor comprising an annular row of thin resilient flexible blades each having a straight cutting edge extending generally axially of said row, said blades being curved circumferentially of said row, means spaced from the cutting edge of each blade for securing said blades in said row with the portion of each blade along its cutting edge being free for movement generally radially outwardly thereof against the tension of the blade whereby the cutting edge of each blade may be moved from a position directed substantially circumferentially of said row to a position directed tangentially thereof, said means including a member within said row coaxial therewith against which said blades are held under the inherent resiliency of each blade.

11. A blade supply magazine for a safety razor comprising an annular row of thin resilient flexible blades each having a straight cutting edge extending generally axially of said row, said blades being curved circumferentially of said row, means spaced from the cutting edge of each blade for securing said blades in said row with the portion of each blade along its cutting edge being free for movement generally radially outwardly thereof against the tension of the blade whereby the cutting edge of each blade may be moved from a position directed substantially circumferentially of said row to a position directed tangentially thereof, said means including

a cylindrical member within said row coaxial therewith against which said blades are held under the inherent resiliency of each blade with the cutting edges of said blades facing in the same direction circumferentially of said row.

12. In a safety razor, a blade supply magazine comprising an annular row of thin resilient flexible blades each having a straight cutting edge extending generally axially of said row, said blades being curved circumferentially of said row, means spaced from the cutting edge of each blade for securing said blades in said row with the portion of each blade along its cutting edge being free for movement generally radially outwardly thereof against the tension of the blade whereby the cutting edge of each blade may be moved from a position directed substantially circumferentially of said row to a position directed tangentially thereof, and means carried by said razor within said row movable generally radially outwardly thereof into engagement with said blades for causing said movement of any one of said blades as desired.

13. A blade supply magazine for a safety razor comprising an annular row of thin, resilient, wafer type razor blades each having a straight cutting edge extending generally axially thereof and facing substantially circumferentially of said row in close overlying relation to the blade adjacent thereto, said blades being curved circumferentially of said row, means spaced from the cutting edge of each blade for securing said blades in said row with the portion of each blade along its cutting edge being movable generally radially outwardly thereof against the tension of the blade whereby each blade may be flexed against its tension to move its cutting edge from a position directed substantially circumferentially of said row to a position directed tangentially thereof and spaced from the blade which said edge overlies.

14. In a safety razor, a blade supply magazine comprising an annular row of thin, resilient, wafer type razor blades each having a straight cutting edge extending generally axially thereof and facing substantially circumferentially of said row in close overlying relation to the blade adjacent thereto, said blades being curved circumferentially of said row, means spaced from the cutting edge of each blade for securing said blades in said row for rotation thereof with the portion of each blade along its cutting edge being movable generally radially outwardly thereof against the tension of each blade whereby each blade may be flexed against its tension to move its cutting edge from a position directed substantially circumferentially of said row to a position directed tangentially thereof and spaced from the blade which said edge overlies, radially outwardly movable spring urged means within said row adjacent one side thereof in yieldable engagement with the radially inwardly facing side of the blade adjacent thereto for causing said movement of the cutting edge of said blade.

15. A safety razor comprising a casing, a plurality of relatively thin resilient razor blades arranged in a row within said casing with said blades curved circumferentially of said row, means supporting said blades within said casing for revolution about the axis of said row, each of said blades being formed with a straight cutting edge extending axially of said row, said casing being formed with an opening in one side thereof extending longitudinally of said axis, means within said casing for moving the cutting edge of each blade into position outwardly of said row

75 for movement through said opening upon revolving the blades of said row about said axis.

16. A safety razor comprising a casing, a plurality of relatively thin resilient razor blades arranged in a row within said casing with said blades curved circumferentially of said row, means supporting said blades within said casing for revolution about the axis of said row, each of said blades being formed with a straight cutting edge extending axially of said row, said casing being formed with an opening in one side thereof extending longitudinally of said axis, means within said casing for moving the cutting edge of each blade against the tension of the latter into a position outwardly of said row for movement of said edge tangentially of said row through said opening upon revolution of said blades about said axis.

17. A safety razor comprising a casing, a plurality of relatively thin resilient razor blades arranged in a row within said casing with said blades curved circumferentially of said row, means supporting said blades within said casing for revolution about the axis of said row, each of said blades being formed with a straight cutting edge extending axially of said row, said casing being formed with an opening in one side thereof extending longitudinally of said axis, means within said casing for moving the cutting edge of each blade against the tension of the latter into a position outwardly of said row for movement of said edge generally tangentially of said row through said opening upon revolvable movement of each blade in one direction to a point adjacent said opening.

18. A flexible, resilient wafer-type safety razor blade having a straight cutting edge and an opposite rear edge and being precurved to said edges with a substantially uniform radius of curvature in its dimension at right angles to said edges for self retention of said curve, the length of said radius of curvature being less than said dimension, a pair of oppositely outwardly extending ears adjacent said rear edge and projecting outwardly of the ends of said cutting edge, said ears being adapted to be grasped for holding said blade rigid along said rear edge to permit flexing said blade to a relatively flat shape by applying an outwardly directed force on the remainder of said blade relative to the center of curvature thereof.
